CANDLE

Hubert A. Shaw, Hyannis, Mass.

Application October 26, 1948, Serial No. 56,623

4 Claims. (Cl. 67—22)

1

This invention relates to improvements in candles of relatively large diameter. Such candles by reason of their bulk contain a large amount of wax and can therefore burn for long periods, even when made with a plurality of wicks as is done in some cases. In addition to their ornamental uses, some candles may have odor-producing ingredients added to the wax, such, for example, as a perfume, a deodorant, an antiseptic or an insect repellent.

When candles of large diameter are burned for considerable periods, a pool of melted wax is formed which may gradually attain considerable size. To prevent such pools of melted wax from escaping and thus greatly shortening the life of the candle, candles of large diameter have been made with a surface layer of wax having a higher melting point than that of the inner wax which forms the bulk of the candle.

According to the present invention, instead of the casing of higher melting-point wax, a casing of bright metal foil is provided. Such foil can be readily shaped into the form of a dish or cup, and the candle can be formed by pouring melted wax into the casing, using the latter as a mold; or a previously molded candle can be inserted in the casing. The bright metal foil not only prevents the escape of melted wax when the candle is burning, but also helps to retain in the pool radiant heat from the flame, owing to its bright, reflective surface. Furthermore, by making an outwardly turned lip or rim on the casing, a highly ornamental halo effect is obtained by reflection of light from the flame.

Suitable casings can be made from discs of metal foil by bending up the marginal portion to the desired angle. This necessitates gathering the bent-up portion by crimping the marginal portion of the blank in the process of bending it up. The crimping may be in the form of flutes or pleats which are preferably so made as to produce an ornamental effect so as to add to the appearance of the finished candle.

For a more complete understanding of the invention, reference may be had to the following description thereof, and to the drawing, of which—

Figure 1 is a perspective view of a receptacle for a candle embodying the invention;

Figure 2 is a fragmentary, sectional view of the same;

Figure 3 is a fragmentary, sectional view of a complete candle embodying the invention;

Figure 4 is a fragmentary, side elevation of a modified form of receptacle;

2

Figure 5 is a fragmentary, side elevation of another modified form of receptacle; and

Figure 6 is a section similar to Figure 3 but showing a modification.

The candle embodying the invention may comprise a body of wax 10 fitted within a receptacle 12 and provided with one or more suitable wicks 14. The receptacle 12 is of bright metal foil and is preferably made by shaping a circular blank of such metal into a form such as is illustrated in Figure 1. When the marginal portion of such a blank is bent up to form the side walls 16 and an outwardly curled rim or lip 18 of the receptacle, this portion must necessarily be gathered in some manner as the outer circumference of the margin decreases as it is bent upward and inward. As indicated in Figure 1, the gathering may result in the formation of a series of flutes or crimps 20 which extend upward from the bottom of the wall and which become increasingly pronounced in depth as they extend toward the upper edge. These flutes or crimps provide a considerable degree of mechanical stiffness to the walls of the receptacle, making possible the use of relatively thin foil. Part way up the side wall, each flute is preferably shaped into a plurality of smaller flutes 22, these small flutes being carried over the outwardly curled lip 18 to the extreme edge thereof. This results in a rim or lip 18, all of which is evenly wrinkled or fluted. When one or more flames are burning from the wicks in the candle, these rounded flutes or wrinkles reflect the light and produce an attractive halo effect.

The candle can be made by pouring melted wax into a receptacle, such as is illustrated in Figure 1, and allowing the wax to solidify. While the wax is still in liquid form, a suitable number of wicks 14 may be inserted. For convenience, each such wick may be previously attached at its lower end to a small metal anchor 24 to support it in an upright position prior to the solidification of the wax.

As an alternative method of assembling the wicks with the main body of the wax, each wick 14 may be previously incorporated into a small cylinder 26 of wax having a higher melting point than that of the main body of wax 10. When the main body of wax begins to solidify, the small wax cylinders 26 can be thrust in at the desired points.

Figures 4 and 5 show alternative methods of gathering the material in the side walls of the receptacle during the bending-up process. Figure 4 shows simple pleats 30 which are continuous and

of increasing width from the bottom of the side wall to the upper edge thereof. The upper margin is outwardly curled to form a rounded lip 32, as shown. Figure 5 shows box pleats 34, the upper margin being outwardly bent down to form a rim 36, as shown.

If preferred, the body 10 of wax can be previously molded to a shape adapted to fit into the receptacle and the molded body of the wax can be placed in such receptacle. To make the wax body stick in the container, the bottom surface can be momentarily heated to form a liquid film thereon just before it is inserted in the receptacle, or a coating of binding material may be applied to the interior of the receptacle.

Any desired wax or wax mixture can be used, having any desired color or added ingredient, such as a perfume, a deodorant or an insect repellent.

It is evident that various other modifications and changes can be made in the embodiment of the invention herein shown and described without departing from the scope thereof as defined in the following claims.

I claim:

1. A candle comprising a casing of bright metal foil with bent-up sides and an outturned lip, a body of wax substantially filling said casing, and a wick embedded in said wax.

2. A candle comprising a dish-shaped casing of bright metal foil having crimped side walls and a crimped outturned lip, a body of wax substantially filling said casing, and a wick embedded in said wax.

3. A candle comprising a dish-shaped casing of metal foil having a bent-up side wall with a series of upright flutes extending up from the bottom thereof and a larger number of smaller flutes in the upper portion thereof, said casing having an outturned fluted rim, a body of wax fitted in said casing, and a wick embedded in said wax.

4. A candle comprising a casing of metal foil, a body of wax fitted in said casing, and a wick embedded in said body of wax; the wax immediately surrounding said wick having a higher melting-point than the bulk of the wax in said body.
